JOSEPH SMALLWOOD, OF ST. JOHN, NEW BRUNSWICK.

Letters Patent No. 79,084, dated June 23, 1868.

IMPROVEMENT IN PORTABLE STOVES.

The Schedule referred to in these Letters Patent and making part of the same.

TO ALL WHOM IT MAY CONCERN:

Be it known that I, JOSEPH SMALLWOOD, of St. John, in the Province of New Brunswick, British North America, have invented a new and improved Pocket Cooking-Stove; and I do hereby declare that the following is a full, clear, and exact description thereof, which will enable those skilled in the art to make and use the same, reference being had to the accompanying drawings, forming part of this specification.

This invention relates to improvements in portable stoves for workmen and others, whereby they are enabled to heat their coffee or tea, and warm their dinners, when laboring in the field or woods.

And it consists in the arrangement of a boiler and furnace, which may be folded or slipped together, as will be hereinafter more fully described.

Figure 1 is a plan view.

Figure 2 is a view of the furnace and the boiler, and the parts connected therewith, folded together in compact form, for transportation or the pocket.

Figure 3 represents the furnace and boiler united, as when arranged for use.

Similar letters of reference indicate corresponding parts.

This stove may be made in any convenient form, and consists of two parts, the furnace A and boiler B, with the cup and spirit-reservoir.

C is a lamp, which is placed in the furnace or fire-box A.

In fig. 2, the lamp is seen packed away in a cup, D, which goes with the stove.

E is a spirit-reservoir, for furnishing the lamp and fire-box with fuel.

f represents orifices through the wall of the furnace, for the ingress of air, and

g represents orifices for the escape of the smoke and heated gases.

When in use, the boiler B is dropped down into the top of the furnace, as seen in fig. 3.

When the stove is being transported or carried from place to place, the boiler B (which is made somewhat tapering for the purpose) is turned bottom side up, and slipped into the furnace, forming a telescopic joint, as seen in fig. 2, thus reducing the size of the article about one-half, and sufficiently to allow it to be placed in the pocket.

I claim as new, and desire to secure by Letters Patent—

The furnace or part A, and the boiler or part B, when constructed so that they will slide or fold together, as seen in fig. 2, and when used for the purposes set forth, or in combination with a lamp, substantially as described.

The above specification of my invention signed by me, this 13th day of April, 1868.

JOS. SMALLWOOD.
